COMBINED LAMP SHADE AND MIRROR

Aime Trudeau, 227 NE. 26th St.,
Miami, Fla. 33137

Filed Jan. 15, 1969, Ser. No. 15,362

Term of patent 14 years

Int. Cl. D26—06

U.S. Cl. D48—16

FIG. 1 of the drawings is a front perspective view of a combined lamp shade and mirror embodying my new design;

FIG. 2 is a right side perspective view thereof,

FIG. 3 is a rear perspective view thereof, and

FIG. 4 is a left side perspective view thereof.

The lamp stand is shown in broken lines in FIGS. 1—4 for illustration purposes only.

I claim:

The ornamental design for a lamp shade and mirror, as shown and described.
